UNITED STATES PATENT OFFICE.

EDWARD POSSON, OF CHICAGO, ILLINOIS.

SEALING LOCK AND DOOR STARTER.

Application filed January 28, 1922. Serial No. 532,514.

To all whom it may concern:

Be it known that I, EDWARD POSSON, a citizen of the United States, residing at Chicago, in the county of Cook and State of Illinois, have invented certain new and useful Improvements in Sealing Locks and Door Starters, of which the following is a specification.

This invention relates to improvements in apparatus for operating the doors of railway cars and the like, where it is desirable to use means for effecting a positive movement of the door and for securing the locking mechanism in position.

The principal object of the invention is to provide means for locking the car door either in closed or partially open position. A further object is to provide improved operating mechanism for effecting a positive initial opening movement of the door and a positive final closing movement thereof. A further object is to provide improved door operating mechanism in combination with improved means for locking it in position on the car wall. Other objects relate to various features of construction and arrangement which will appear more clearly hereinafter.

The nature of the invention will be understood from the following specification taken in connection with the accompanying drawings, in which one embodiment is illustrated.

In the drawings—

Figure 1 shows a partially enlarged side elevation of a car wall and car door with the invention applied thereto;

Fig. 2 shows a horizontal section, taken on the line 2—2 of Fig. 1, illustrating a top plan view of the invention.

Fig. 3 is a detail sectional view, taken on the line 3—3 of Fig. 1, looking in the direction of the arrows.

Fig. 4 is a detail sectional view, taken on the line 4—4 of Fig. 1, looking in the direction of the arrows;

Fig. 5 shows a perspective view of the door-operating lever;

Fig. 6 shows a partial side elevation of a railway car having the present invention applied thereto;

Fig. 7 is a detail vertical section, taken on the line 7—7 of Fig. 1, looking in the direction of the arrows;

Fig. 8 is a perspective view of the locking bracket or casing which is secured to the door jamb; and

Fig. 9 shows a perspective view of the locking bolt.

The invention is shown in connection with a car door 10 adapted to close the usual door opening in the side walls 11 of a railway car. The upper edge of the door travels in a guideway 12 secured to the car wall, and the lower part of the door has brackets or hangers 13 secured thereto and carrying rollers which travel on the horizontal track 14 and support the door in its movement. Handles 15 are secured to the door for permitting convenient operation thereof. The door is also reinforced by horizontal bars 16, which are secured thereto adjacent its upper and lower edges. The leading edge of the door is adapted to seat against a door jamb 18, which is secured to the outer side of the usual door post 19, extending vertically at the side of the door opening. The face 18^a of the door jamb is offset from the inner face of the door post, so that the edge of the door is adapted to overlap the door post, as shown at 20. The inside sheathing 21 and the outside sheathing 22 of the car wall are secured to the door post in the usual manner, and a filler plate 23 is inserted between the outside sheathing and the door jamb, as shown particularly in Fig. 2. A metal plate 24 is secured to the outer face of the door jamb 18 and extends vertically thereof, being arranged to project beyond the face 18^a of the door jamb, thus forming a vertical guideway to receive the leading edge of the door.

The door 10 is operated by a lever 25, having an aperture 26, which is pivotally engaged by a pin 27 which passes through the outer flange 28^a and the inner plate 28^b of the bracket 28. This bracket is secured to the car door by means of rivets 29, and the plate 28^b of the bracket is preferably seated on the outer side of the horizontal reinforcing bar 30, which extends longitudinally of the door throughout its width, as shown in Fig. 6. The aperture 26 in the lever 25 is somewhat loosely engaged by the pin 27, and has some freedom of movement between the flanges 28^a and 28^b of the bracket, so that it can be swung outwardly to some extent away from the car wall. The body portion of the lever is provided with two vertical apertures 32 and 33 of rectangular cross section, which are formed through the enlarged parts 34 and 35 thereof. Reinforcing ribs 36 extend longitudinally of the lever,

A vertical flange 37 extends inwardly from the lever adjacent the aperture 32, and two other flanges 37 extend inwardly from the lever adjacent the aperture 33 for purposes 5 hereinafter described.

The lever is adapted to engage a locking bracket or casing 40, which seats upon the outer side of the plate 24, secured to the door jamb. This bracket comprises a base plate 10 41, which seats upon the vertical plate 24, being provided with a downwardly extending flange 41^a and a laterally extending flange 41^b which have apertures 42 and 43 therethrough respectively, adapted to be 15 engaged by bolts 44 and 45, respectively, which extend inwardly through the door jamb and through the door post. This bracket is further provided with two outwardly extending bosses 46 and 47, which 20 have vertical alining apertures 48 and 49, of rectangular cross section, extending therethrough. These bosses are spaced apart vertically to leave an intervening slot or notch 50 adapted to receive the lever 25, and the 25 alining apertures 48 and 49 are adapted to receive a vertically slideable locking member 51, which may engage either one of the apertures 32 or 33 formed through the lever. The locking member 51 has an outwardly 30 turned flange 52, at the upper end thereof, which overlaps the upper boss 46 and limits the downward movement of the bolt. The locking member is also provided with a longitudinal slot 53, adapted to be engaged 35 by the bolt 54 which extends through apertures 55 in the walls of the boss 46 and thence horizontally through the door post and jamb, as shown in Figs. 4 and 7. The base plate 41 of the casing 40 has a vertical 40 flange 56 projecting outwardly from the inner edge thereof between the bosses 46 and 47.

When the aperture 32 in the lever 25 is 45 engaged by the locking member 51, the flange 37 of the lever engages the inner side 56^a of the flange 56, thus holding the door against movement and releasing the strain upon the locking member 51. When the aperture 33 in the lever 25 is engaged by the 50 locking member 51, thus holding the door in a partially open position, the flanges 38 of the lever engage the opposite sides of the flange 56, and thus provide a rigid connection between the casing 40 and the locking 55 lever when the door is in that position. The locking member 51 may be secured in its downward position by means of the usual car seal 57, which engages the slots 58 in the side walls of the boss 47, and a similar slot 60 59 which passes through the lower part of the member 51. The lower portion of the locking member is also provided with an aperture 60, which intersects the slot 59, and an opening 61 is provided in the outer wall 65 of the boss 47 to register with the opening

60 when the member 51 is in its lower position, so that access can be had to the parts of the car seal within the boss 47, for convenience in removing the parts of a broken seal, for example. A more secure locking 70 of the member 51 may be effected by means of a padlock 62 which is adapted to engage registering apertures in the ears 63 and 64, which are formed on the casing 40 and the member 51, respectively. 75

The positive opening and closing movements of the door, when it is near the door post, are effected through the upwardly extending arm 65 of the lever 25. This arm extends between the flanges 66 of a rod 67, and is pivotally connected thereto by means of a bolt or rivet 68. The web 69, which unites the flanges 66, is V-shaped in cross section, as shown in Fig. 1, so that it engages the inclined arm 65 and prevents the downward swinging of the rod 67. This rod is provided with an enlarged head 67^a having a notch or recess 70 cut in the under side thereof, adapted to engage the boss 71 formed on the upper part of the casing 40 around the aperture which is engaged by the bolt 54. When the notch in the rod engages this boss an operating connection is formed between the rigid door post and the pivot of the lever 25, so that when this lever is swung outwardly from the notch 50 of the casing 40, after upward movement of the locking member 51 to the extent permitted by the slot 53, the pivotal movement of the lever then operates to effect a positive movement of the door toward or away from the door jamb. 90

When the door is in a partially open position the rod 67 is supported in position substantially parallel to the lever 25 by a V-shaped web 69 resting on the arm 65 of the lever. When the door reaches a position near the door post, the rod 67 can be swung upwardly from the lever to cause the notch 70 thereof to engage the boss 71, whereupon an upward swinging of the lever will effect a positive movement of the door toward the door jamb. In a similar way the downward swinging of the lever, with the notch 70 engaging the boss 71, will effect a positive movement of the door away from the door jamb. 110

Although I have shown and described one form of the invention for purposes of illustration, it will be understood that it may be constructed in various other embodiments without departing from the scope of the appended claims. 120

I claim:—

1. In an operating and locking mechanism 125 for a door member having a frame member associated therewith, the combination with an operating element movably mounted on one of said members; of means swingable in a plane substantially parallel to the plane 130

of the door for detachably connecting said operating element to the other member; and independent means for locking said operating element to said last named member

5 in a plurality of positions to hold the door either in partly open or tightly closed position.

2. In an operating and locking mechanism for a door member having a frame member 10 associated therewith, the combination with an operating element movably mounted on one of said members; of means for detachably connecting said operating element to the other member; independent means for 15 locking said operating element in a plurality of different positions to hold the door member either in partly open or tightly closed position; and means associated with said operating element and said detachable means 20 for maintaining the latter in predetermined position when the door is partly open.

3. In combination, a frame member, a door, an operating member secured to said door, a locking member engaging said operating member for connecting it to said frame member, said operating member having a part projecting therefrom, and means attached to said frame member for engaging said projecting part.

30 4. In combination, a frame member, a door, an operating member secured to said door, a locking member engaging said operating member for connecting it to said frame member, said operating member having a pair of flanges projecting therefrom, and a plate secured to said frame member and adapted to project between said flanges when said operating member is engaged by said locking member.

40 5. In combination, a frame member, a door, an operating member connected to said door and having a plurality of apertures therethrough, a lug projecting from said operating member adjacent each aperture, a casing connected to said frame member, a locking member mounted in said casing and adapted to engage any one of said apertures in said operating member, and a flange projecting from said casing and adapted 50 to engage the lug adjacent the engaged aperture.

55 6. In combination, a frame member, a door, an operating member pivotally mounted on said door and having an aperture therethrough, a casing secured to said frame member, a locking member slidably mounted in said casing and adapted to engage said aperture, said casing and said locking mem-

ber having apertured parts to be engaged by a padlock.

7. In combination, a frame member, a door, an operating lever connected to said door and having an aperture therethrough, a casing mounted on said frame member and having a recess adapted to receive said operating member, and a locking member slidably mounted in said casing and adapted to engage the aperture in said lever, said locking member and said casing having alining apertures adapted to receive a car seal, 60 said casing and said locking member having other apertured parts adapted to receive a padlock.

8. In an operating and locking mechanism for a door member having a frame member 75 associated therewith, the combination with an operating element movably mounted on one of said members; of rigid means for detachably connecting said operating element to the other member; and independent 80 means for locking said operating element to said last named member in a plurality of different positions to hold the door either in partly opened or tightly closed position.

9. In an operating and locking mechanism 85 for a door member having a frame member associated therewith, the combination with an operating element movably mounted on one of said members for opening and closing said door member; of means 90 for locking said operating element in a plurality of different positions to hold the door member either in partly opened or tightly closed position, said means including a bracket having elements between which said 95 operating member is adapted to be disposed and a locking pin co-operating with said bracket and said operating element.

10. In an operating and locking mechanism 100 for a door member having a frame member associated therewith, the combination with an operating element movably mounted on one of said members; of means 105 for detachably connecting said operating element to the other member whereby said door member may be moved in an opening or closing direction; and means for locking said operating element to hold the door in tightly closed position, said means being arranged to lock said operating member subsequent to its movement in a door opening direction to lock the door member in partly 110 open position.

In testimony whereof, I have subscribed my name.

EDWARD POSSON.
